UNITED STATES PATENT OFFICE.

CHARLES H. HERTH, OF MEMPHIS, TENNESSEE, ASSIGNOR TO BALING TIE BUCKLE COMPANY,
OF MEMPHIS, TENNESSEE.

WIRE-PULLER.

No. 903,818.

Specification of Letters Patent.

Patented Nov. 10, 1908.

Application filed May 27, 1908. Serial No. 435,348.

To all whom it may concern:

Be it known that I, CHARLES H. HERTH, a citizen of the United States, residing at Memphis, in the county of Shelby and State 5 of Tennessee, have invented a new and useful Wire-Puller, of which the following is a specification.

This invention relates to improvements in wire pullers and more particularly to the 10 kind used in drawing wire around bales, packages, cases and the like.

One object of the present invention is to provide a hand device that will freely move over the wire when moved in one direction, 15 and by a reverse movement automatically clutch or grip the same.

Another object is to construct a device the mechanism of which will tend to increase the grip on the wire during the operation of 20 pulling the latter taut around a bale or the like.

Another object is to provide a device simple in construction and embodying comparatively few parts.

25 With these and other objects in view as will more fully hereinafter appear the present invention consists in certain novel details of construction and arrangement of parts hereinafter fully described, illustrated in the 30 accompanying drawings, and particularly pointed out in the appended claims it being understood that various changes in the form, proportion, size and minor details of the device may be made without departing from 35 the spirit or sacrificing any of the advantages of the invention.

In the drawings:—Figure 1 is a longitudinal sectional view showing the gripping mechanism. Fig. 2 is a similar view taken 40 on line 2—2 Fig. 1. Fig. 3 is a detached perspective view of the gripping mechanism. Fig. 4 is a similar view of the cap. Fig. 5 is a perspective of the retaining collar. Fig. 6 is a similar view of the pusher, and Fig. 7 45 is a perspective of the spring for actuating the pusher.

Similar numerals are employed to designate the corresponding parts throughout.

In the construction illustrated in Figs. 1 50 and 2 a handle 1 preferably formed of wood or other suitable material and of the usual shape is centrally provided with a longitudinal bore 2 extending from the lower or smaller end 2^a, and terminating at the upper

or larger end 3^a. On the lower end 2^a a ferrule 3 of an interior diameter adapted to snugly fit over the end 2^a is provided, and on the lower or bottom end of the ferrule is a projection 4, of an exterior diameter considerably less than said ferrule. The projection 60 is centrally provided with a longitudinal bore in direct alinement with the bore 2 of the handle and terminating in outwardly inclined walls 5 forming a bore of a greater diameter than the bore of the handle. 65

Adjacent the opposite or larger end 3^a of the handle a transverse recess 6 is formed the function of which will presently appear. The upper face 3^a is countersunk forming a central circular seat flanked by the shoulder 70 7. A circular pedestal or support 8 of an exterior diameter somewhat less than the end 3^a of the handle is provided with a reduced portion 9 adapted to snugly fit within the seat formed in the upper end of the handle. 75 The support is centrally provided with a bore alining with the bore 2 of the handle. The support is secured in the seat by means of bolts or screws 10 entering alining perforations formed in the support and handle on 80 either side of the bore 2 and terminating in the transverse recess 6 into which nuts 11 are inserted for the ends of the screws 10. On the upper face of the support 8 are two cheeks 12 preferably formed integral with 85 the support and projecting at right angles to the upper or outer face thereof. The cheeks extend transversely of the support and are disposed on either side of the central bore 2. Mounted between the cheeks 12 on pivots 15 90 and 16 disposed adjacent the opposed ends of said cheeks is a pair of gripping members 13 and 14 having enlarged heads each provided with a cam surface the greater portion of which is serrated as shown at 17, and terminating in reduced handle portions 18 and 19, intermediately bent at substantially obtuse angles and forming finger pieces 20 and 21. It is to be observed that the openings in the heads 13 and 14 are a trifle to one side of the 100 longitudinal center so that the finger pieces will normally lie parallel to the handle 1.

A collar 22, of an exterior diameter equal to that of the handle 1 and an interior diameter considerably greater than the exterior of 105 the support 8 is provided with a pair of diametrically opposite recesses 23 which receive the handles 18 and 19.

A cap 24 of an exterior diameter equal to that of the collar 22 is provided with a reduced portion 25 of slightly less exterior diameter than the interior of the collar 22, and is adapted to be inserted between the inner face of said collar and exterior of the support 8, as clearly shown in Figs. 1 and 2. The head 26 of the cap is provided with a bore alining with but of greater diameter than the bore 2 and is further provided with a pair of longitudinal recesses extending inwardly from the lower end, and adapted to register with the recesses 23 formed in the collar 22. The head 26 of the cap lies considerably beyond the upper edges of the cheek plates 12 forming a chamber for the reception of the grip actuating mechanism, which is shown in the present instance to consist of a pusher preferably formed of a metallic disk 27 adapted to slidably fit within the cap 24 and centrally provided on one face with a nipple 28 adapted to slidably fit into the opening formed in the head 26 of the cap.

25 A helical spring 29 is adapted to encircle the nipple 28 its terminals resting on the inner face of the head 26 of the cap and disk 27.

When assembling the parts, the support 8 is first secured to the handle by means of the screws 10 thus retaining the grippers in the position shown in Fig. 3. The pusher 27 and spring 29 are then inserted in the cap 24 and the reduced end of the latter forced between the collar and support. This action 35 will bring the pusher in contact with the heads 13 and 14 of the grippers forcing the latter into the space between the cheeks 12 to a position approximately flush with the upper edges of said cheeks. The parts are then 40 secured in place by means of screws 30 entering registering openings formed adjacent the lower edge of the collar 22 cap 25 and support 8 as clearly shown in Fig. 2.

In order to prepare the device for use, the 45 finger pieces 20 and 21 are squeezed inwardly by the fingers of one hand. This movement widens the distance between the serrated faces of the heads 13 and 14 and at the same time raises the pusher 27 50 against the action of the spring 29 and forces the end of the nipple 28 farther outward. The free end of the wire 31, to be used is now inserted through the bore of the nipple thence down between the serrated 55 faces of the grippers, into the bore 2 and out the lower end 5, the pressure on the finger pieces is then released and as the latter are moved outwardly by the force of the spring 29 through the pusher 27, the 60 serrated faces engage the wire 31. It is obvious when the parts are in this position and that part of the wire beyond the end 5 in position to be pulled taut around a bale or the like a pull on the handle 1 in the 65 direction indicated by the arrow in Fig. 1

of the drawing will cause the serrated faces of the grippers to move inwardly thereby increasing their hold upon the wire, this they will continue to do as the pull on the wire increases.

70

What is claimed is:

1. In a wire puller the combination with a handle having a longitudinal bore, a ferrule on one end of said handle having a bore in alinement with the bore of the handle, 75 wire gripping mechanism housed within the opposite end of said handle and provided with the bore in alinement with the bore of the handle and ferrule.

2. In a wire puller the combination with 80 a handle having a longitudinal bore, a ferrule on one end of said handle provided with a projection having a tapering bore in alinement with the bore of the handle, a support housed within the opposite end of the handle, and wire gripping mechanism carried by the support, said support being provided with a bore in alinement with the bores of the ferrule and handle.

3. In a wire puller the combination with 90 a handle, a support housed within the handle at one end thereof, and wire gripping members pivotally mounted on said support and having their gripping faces yieldingly held in gripping position.

4. In a wire puller the combination with 95 a handle, a support housed within the handle at one end thereof, and pivoted wire gripping members having roughened surfaces yieldingly held in gripping position.

5. In a wire puller the combination with 100 a handle, a support housed within the handle at one end thereof and having spaced cheeks on one face thereof, gripping members having opposed serrated surfaces piv- 105 otally secured to said cheeks, and means for yieldingly holding said gripping members in wire gripping position.

6. A wire puller embodying a handle, a support entirely housed within the handle, 110 wire gripping members pivotally mounted on the support and having enlarged heads terminating in flattened finger pieces extending beyond the vertical plane of said handle.

7. A wire puller embodying a support, serrated gripping members pivotally mounted thereon and having enlarged heads terminating in finger pieces projecting beyond the vertical plane of said support, and a 120 pusher normally and yieldably bearing against the heads of the gripping members and provided with a wire receiving seat.

8. A wire puller embodying a handle provided with a longitudinal bore, a support 125 housed within the handle at one end thereof and having a bore in alinement with the bore of the handle, spaced plates on said support, and gripping members pivotally mounted between said plates and having opposed ser- 130

rated ends terminating in reduced shank portions projecting beyond the longitudinal plane of said handle.

9. A wire puller embodying a handle having a support on one end thereof, gripping members pivotally mounted on said support, a cap fitting over the support and means on the interior of said cap adapted to yieldingly hold said gripping members in wire gripping position.

10. A wire puller embodying a handle having a support on one end thereof, gripping members pivotally mounted on the sup-

port, a collar on said handle encircling said support, a cap provided with a portion 15 adapted to fit between said collar and support, and a means on the interior of said cap adapted to yieldingly hold said gripping members in wire gripping position.

In testimony that I claim the foregoing as 20 my own, I have hereto affixed my signature in the presence of two witnesses.

CHARLES H. HERTH.
